CIRCUIT INTERRUPTER

Harry J. Lingal, Forest Hills, and James M. Cumming, Turtle Creek, Pa., assignors to Westinghouse Electric Corporation, East Pittsburgh, Pa., a corporation of Pennsylvania

Application February 1, 1945, Serial No. 575,714

2 Claims. (Cl. 175—294)

1

This invention relates in general to electric circuit interrupters, and more especially to such interrupters which are designed for automatic high-speed reclosing.

In order to meet modern requirements for high-speed reclosing of an automatic reclosing circuit breaker, it has been proposed that the breaker be closed before it reaches its full open position upon a circuit interrupting operation, preferably, that the reclosing be initiated at a point substantially midway between normal fully closed and fully open positions. However, this imposes a heavy duty on the reclosing means because it must not only overcome the contact opening spring, but must be capable of sustaining the sudden heavy shock in attempting to suddenly reverse movement of the movable contact of the breaker, and to do this the kinetic energy of all the moving parts of the breaker must be absorbed, and thereafter these parts must be moved and accelerated in the opposite direction. In the usual breaker, therefore, much time is lost after the breaker contacts are stopped in a mid-open position, before the actuating mechanism can accelerate the parts to close the breaker contacts.

Accordingly, one object of this invention is to reduce the duty on reclosing means for an automatic reclosing circuit breaker when such reclosing means is energized at an intermediate point in the opening movement of the breaker contacts.

Another object of this invention is to provide a relatively high mechanical advantage for circuit breaker actuating mechanism at a mid-stroke position to decrease the time required to close the breaker contacts from this position.

Another object of this invention is to provide in high-speed automatic partial-stroke reclosing circuit breakers, novel actuating mechanism having its greatest mechanical advantage substantially at a point midway of the normal operating stroke of the movable breaker contact between closed and full open positions.

A more specific object of this invention is to provide novel, but simple, actuating linkage for a circuit breaker which is capable of automatically reclosing the breaker contacts at a point intermediate the ends of movement thereof in a normal circuit interrupting operation, which linkage provides the most favorable arrangement to produce high-speed movement substantially at said intermediate point.

These and other objects of this invention will become more apparent upon consideration of the following detailed description of a preferred em-

2

bodiment thereof, when taken in connection with the attached drawing, in which:

Figure 1 is a longitudinal sectional view of a circuit breaker tank, with the breaker mechanism comprising this invention illustrated in elevation;

Fig. 2 is a schematic diagram of an automatic reclosing circuit breaker system for controlling operation of the breaker shown in Fig. 1; and
10 Fig. 3 illustrates characteristic power curves of a breaker constructed in accordance with this invention and prior art constructions.

The circuit breaker 4 shown on the drawing is illustrated as having the contacts and certain of 15 the operating mechanism thereof mounted within a metal tank 2 which is adapted to be filled with an arc extinguishing liquid substantially up to the level L. Tank 2 is provided with a cover 4 adapted to be releasably secured in position, for 20 example by bolts 5, and the cover is adapted to support the breaker contacts and that part of the operating mechanism located within tank 2. Tank cover 4 is provided with apertures for the 25 reception of bushings 6 of insulating material, such for example as porcelain or the like; and the bushings are constructed in a well known manner with a conductor rod extending through a longitudinal passage therein to support within tank 2, stationary contact and arc extinguishing 30 structures 8, in spaced relation. Contact structures 8 are adapted to be bridged by a movable 35 bridging contact bar 10 mounted on the lower end of a lift rod 12, for movement with the rod into and out of bridging relation with respect to contact structures 8. Lift rod 12 is of an insulating material, such as a molded insulated material, and is adapted to move bridging contact bar 10 from the closed circuit position shown in full lines to the full open circuit position shown by dot and dash lines in Fig. 1, or from the open position 40 shown by the dot and dash lines in Fig. 1 to the closed position shown by the full lines in Fig. 1.

In order to guide lift rod 12 for substantially rectilinear reciprocating movement, tank cover 4 45 has secured within a hollow portion 18 thereof a pair of spaced guide members 14, which are adapted to guide the upper end of lift rod 12 therebetween. For this purpose, the upper end of lift rod 12 may be provided with a guide roller 50 16 rotatably mounted on a pivot pin 22. Guide members 14 are provided with guide rollers 11 at their lower ends for guiding an intermediate portion of lift rod 12, and have their lower ends joined by a connecting bar 15. A floating actuating lever 20 is adapted to be connected to the 55

upper end of lift rod 12, for example as by pivot pin 22, and the other end of the actuating lever is pivotally supported as at 24 by a supporting lever 26, with the supporting lever 26 being pivotally mounted on an actuating shaft 28 for movement relative to the shaft. Actuating shaft 28 extends transversely of the hollow portion 18 of cover 4 and has one end extended outside of the cover to be connected with an actuating lever 36, which may be motivated by a connecting link 38 adapted to be connected to a closing solenoid or the like. Floating actuating lever 20 is adapted to be actuated by toggle lever 30 and link 32 pivotally connected together by a knee pivot pin 34, with link 32 pivoted to an intermediate point on floating actuating lever 20, and with toggle lever 30 rigid with actuating shaft 28. Preferably, a coil spring 43 is provided, reacting between the upper end of lift rod 12 and cover 4, to bias contact bridging bar 10 to the full open circuit position shown in the dot and dash lines in Fig. 1.

In the operation of the structure shown in Fig. 1 of the drawing, the breaker mechanism is normally latched in the closed circuit position shown in full lines in Fig. 1, by means to be hereinafter described. It will be apparent that when such latching means is released, spring 43 will be free to move lift rod 12 downwardly and thus actuate contact bridging bar 10 to the full open circuit position shown in dot and dash lines. In order to close the breaker contacts, it will be necessary to exert a force on connecting link 38 in a direction downwardly as viewed in Fig. 1, to rotate actuating shaft 28 in a counterclockwise direction. Such rotation of actuating shaft 28 will cause toggle lever 30 to lift floating lever 20 through toggle link 32, and since the outer end of floating lever 20 is constrained for rectilinear movement by guides 14, lifting of this lever by the toggle links causes it to assume various angular positions during its movement corresponding to movement of contact bridging bar 10 from the full open to the closed circuit position. It will be noted that as the breaker contact bridging bar 10 moves between the full line position and the position shown by dot and dash lines that toggle lever 30 and link 32 will assume a substantially right angle relation when the bridging contact bar 10 is at a point intermediate its closed circuit position and its full open circuit position. Consequently, at such intermediate position, preferably at a point substantially midway between the ends of the path of movement of bridging contact bar 10, the motive means applying force to connecting link 38 will be most effective to move contact bridging bar 10, because the ratio of breaker travel to travel of the solenoid or other actuating means is a minimum at such intermediate position as shown by curve 82 in Fig. 3. This means that the actuating means is able to stop circuit opening movement of the breaker parts and accelerate them in a circuit closing direction in less time than conventional mechanisms having a high ratio of breaker travel to solenoid travel, at mid-stroke, such as the mechanism illustrated by curve 80 in Fig. 3.

Conventional mechanisms for obtaining straight line movement of a circuit breaker lift rod generally have a ratio of breaker travel to solenoid travel which varies from about 5:1 at the full open position of the breaker contacts, to 1:1 at the closed position of the breaker, as illustrated by curve 80 in Fig. 3. This means, by

way of example, that a force of five pounds would have to be exerted on connecting link 38 in order to move the breaker closed, if the breaker had a resistance of one pound at the fully open position, and at the closed circuit position the full five-pound force would be applied to the breaker contacts. However, at mid-stroke, it would be evident that after a breaker travel of about 2½ inches, assuming a five-inch stroke, the mechanical disadvantage would be about 3.25:1 as shown by curve 80. The curve for the mechanism illustrated in Fig. 1 is designated 82 in Fig. 3, and obviously has quite a different characteristic than the conventional mechanism typified by curve 80. The curve 82 is notable in that the mechanical disadvantage is substantially decreased at mid-stroke. This means that the power available at mid-stroke is considerably raised, which is of especial importance in connection with a partial stroke automatic reclosing circuit breaker, as will be hereinafter described. Thus, assuming the power available to reclose to be 1000 pounds, then the power obtained at mid-stroke on curve 80 would be only about 307 pounds, whereas that obtained at mid-stroke on curve 82, with the mechanism illustrated in Fig. 1, would be approximately 690 pounds, or over twice that obtained with conventional mechanisms.

In Fig. 2 there is illustrated diagrammatically a suitable reclosing circuit breaker system for controlling the circuit breaker shown in Fig. 1. A trip coil 40 and closing solenoid 42 are indicated schematically with trip coil 40 adapted to release a latch 41 which normally maintains the breaker contacts in closed circuit position against the bias of opening spring 43. The reference numeral 46 indicates a supply circuit which is arranged to be connected to a load circuit 48 by the circuit breaker 1. A fault responsive relay 50 is connected so as to be energized in accordance with the current flowing through circuit breaker 1. When the current supply to load circuit 48 exceeds a predetermined value, overload relay 50 is arranged to effect energization of trip coil 40, provided the circuit breaker is closed. Also, overload relay 50 initiates the closing operation of the circuit breaker before it has completed the opening operation, preferably, as previously described, this closing operation is initiated substantially at a point midway between full open and closed circuit positions of the breaker contacts. This result is obtained by having relay 50 complete an energizing circuit or instantaneous reclosing circuit for a closing control relay 52, which, in turn, completes an energizing circuit for closing coil 42.

As previously pointed out, a reclosing operation of the breaker 1, which is caused to take place before the breaker bridging contact has attained its full open position, imposes an extremely heavy duty on the closing solenoid, because the momentum of all of the parts which are moved by opening spring 43 during the circuit opening operation must be absorbed, and the movement of these parts rapidly reversed in order to rapidly reclose the breaker contacts. The reason for the particular mechanism illustrated in Fig. 1, having the characteristic curve 82 shown in Fig. 3, will now be apparent, because this particular mechanism affords the lowest mechanical disadvantage at mid-stroke which is the point at which closing solenoid 42 is energized for a partial stroke reclosure by the means shown in Fig. 2,

and thus permits faster reclosing of the contacts.

In order to limit the number of instantaneous partial stroke reclosures of the breaker to a predetermined number which, in the arrangement shown, is one, a lockout relay 54 is provided which, after the initial reclosure maintains the instantaneous reclosing circuit described above for relay 52, open for a predetermined time interval if the circuit breaker remains closed and maintains the instantaneous reclosing circuit permanently open if the circuit breaker remains open at the expiration of the predetermined time interval.

As shown, the operating coil 56 of lockout relay 54 is connected in series with closing coil 42. The operating coil 56 when energized opens the circuit of relay 52 which is completed by overload relay 50, so that a subsequent operation of relay 50 does not affect immediate energization of closing relay 52. Lockout relay 54 is arranged in any suitable manner so that it is held in its energized position after the operating winding 56 is deenergized. In the arrangement shown this result is obtained by means of a latch 58 which holds the relay in energized position, and which is arranged to be released by a release coil 60 when energized.

There also is provided additional automatic reclosing means 76 of any suitable type, for effecting reclosing of the circuit breaker a predetermined number of times with relatively long time intervals between successive reclosures, so that the breaker movable bridging contact moves to full open circuit position each time, in case the breaker does not remain closed after initial reclosure. Reclosing means 76 also is adapted to effect energization of release coil 60 if the breaker remains closed after operation of automatic reclosing means 76 for a predetermined period of time. Such reclosing means 76 may be similar to that disclosed in R. J. Wensley Patent No. 1,786,324, granted December 23, 1930, and assigned to the same assignee of this invention.

The particular reclosing system illustrated in Fig. 2 operates in detail substantially as follows:

Under normal load conditions the breaker remains closed and the control devices are in the positions shown. When an overload occurs overload relay 50 closes its contacts 62 to complete a circuit through the auxiliary contacts 64 on the breaker for energizing trip coil 40 and thus cause release of latch 41 and opening of the breaker by spring 43. At the same time an energizing circuit is completed for reclosing relay 52 through the contacts 66 of relay 50 and the contacts 68 of lockout relay 54. By closing its contacts 70, relay 52 completes a series energizing circuit for closing coil 42 and the operating winding 56 of lockout relay 54. Energization of closing coil 42 results in reclosing of the breaker contacts in the manner previously described. Energization of lockout relay 54 causes opening of its contacts 68 to prevent a subsequent energization of overload relay 50 from effecting another instantaneous reclosure of the circuit breaker.

Closing of the auxiliary contacts 72 of the circuit breaker by initial opening thereof completes a starting circuit 74 for automatic reclosing means 76. If the fault persists when the breaker is reclosed, overload relay 50 again causes its contacts 62 to energize trip coil 40 and thus again open the breaker. Closing of contacts 66 does not close the instantaneous reclosing circuit re-

lay 52, because this circuit is now open at the contacts 68 of the lockout relay.

After the second opening of the circuit breaker a time interval elapses before reclosing means 76 completes a closing circuit 78 for relay 52. When this closing circuit is completed, relay 52 by closing its contacts 70 completes an energizing circuit for closing coil 42 as previously described to effect another closing of the breaker.

The automatic reclosing means 76 is arranged in a manner well known in the art to effect a predetermined number of energizations of closing relay 52, and if the breaker fails to remain closed after this number of reclosures, automatic reclosing means 76 is rendered inoperative to make any further reclosure. If the breaker remains closed before the predetermined number of reclosures has occurred, reclosing means 76 is operative to release latch 58 by energization of circuit 84 to restore lockout relay 54 to its normal position.

It can thus be seen from the foregoing that in an automatic reclosing circuit breaker wherein a predetermined reclosing operation in any sequence of closely successive circuit interrupting operations is instantaneous and of the partial stroke variety, the mechanism disclosed herein permits the use of relatively small reclosing motive means, such as a reclosing solenoid or the like, while rendering such instantaneous reclosure particularly efficient and at a more rapid rate due to the characteristics of the mechanism which renders the force delivered to the contact from the reclosing means to be a maximum at the point in the stroke where reclosure occurs. As previously pointed out, such instantaneous partial stroke reclosing preferably occurs at the mid-point in the stroke of the movable bridging contact bar of the breaker from closed circuit position to full open circuit position. Although the mechanism illustrated has a somewhat higher ratio of breaker to solenoid travel at the closed circuit position than conventional mechanisms, as illustrated in Fig. 3, this is not a disadvantage because it will be observed that the ratio is not as high as at open position, and although greater resistance is encountered than at the open position, advantage may be taken of the kinetic energy of the moving parts adjacent closed position, so that the higher ratio at this position is not detrimental.

Having described a preferred embodiment of the invention in accordance with the patent statutes, it is desired that the invention be not limited to this particular embodiment, inasmuch as it will be apparent to persons skilled in the art that many modifications and changes may be made therein without departing from the broad spirit and scope of this invention, as defined in the following claims.

We claim as our invention:

1. In an automatic reclosing circuit breaker, separable contact means at least one of which is movable and is biased to a full open circuit position, means for releasably holding said movable contact means in closed circuit position and being operable in response to predetermined conditions to release said movable contact means, reclosing means comprising a closing lever connected to said movable contact means, an operating lever for applying force through a connecting link to a fixed point on said closing lever in a direction for moving said movable contact means from full open to closed circuit position, means responsive to a predetermined circuit opening operation of

said breaker to cause said reclosing means to halt opening movement of said movable contact means at a point before said movable contact means reaches full open circuit position and to immediately return said movable contact means to closed circuit position, the fulcrum of one of said levers being movably mounted relative to the fulcrum of the other lever, and a guide for said one lever to shift said movable fulcrum for varying the effective lever arm from the pivot of said operating lever to the said fixed point where it applies force to said closing lever in response to movement of said movable contact means so that this distance is a minimum thereby causing the force delivered to the movable contact means by said reclosing means to be highest substantially at the point in the movement of said movable contact means corresponding to the aforesaid point in the path of movement of said movable contact means where opening movement may be halted.

2. In an automatic reclosing circuit breaker, separable contact means at least one of which is movable and is biased to a full open circuit position, means for releasably holding said movable contact means in closed circuit position and being operable in response to predetermined conditions to release said movable contact means, reclosing means comprising a closing lever connected to said movable contact means, an operating lever for applying force through a connecting link to a fixed point on said closing lever in a direction for moving said movable contact means from full open to closed circuit position, means responsive to a predetermined circuit opening operation of said breaker to cause said reclosing means to halt opening movement of said movable contact means at a point before said movable contact means reaches full open circuit position and to

immediately return said movable contact means to closed circuit position, the fulcrum of one of said levers being movably mounted relative to the fulcrum of the other lever on a pivoted supporting link, and a guide for said one lever to shift said movable fulcrum for varying the effective lever arm from the pivot of said operating lever to said fixed point where it applies force to said closing lever in response to movement of said movable contact means so that this distance is a minimum thereby causing the force delivered to the movable contact means by said reclosing means to be highest substantially at the point in the movement of said movable contact means corresponding to the aforesaid point in the path of movement of said movable contact means where opening movement may be halted.
